UNITED STATES PATENT OFFICE.

WILLIAM R. VAN SLYKE, OF EVELETH, MINNESOTA.

TYPE-WRITER PLATEN.

No. 888,556.

Specification of Letters Patent.

Patented May 26, 1908.

Application filed February 5, 1907. Serial No. 355,881.

To all whom it may concern:

Be it known that I, WILLIAM R. VAN SLYKE, a mining engineer, citizen of the United States of America, residing at Eveleth, in the county of St. Louis and State of Minnesota, have invented new and useful Improvements in Type-Writer Platens, of which the following is a specification.

This invention relates to improvements in typewriter platens, and particularly to the construction of a platen which will materially reduce or completely deaden the noise resulting from the striking of the type bars against the platen.

The object of the invention is to provide a simple construction of platen designed to secure this advantage, and in which the construction is such as to permit ready assemblage of parts in forming the platen and disassembly of the same in making repairs.

In the accompanying drawing, Figure 1 is a longitudinal section of a typewriter platen embodying my invention. Fig. 2 is a plan view of the tubular body thereof. Fig. 3 is an end elevation of the platen. Fig. 4 is a cross section thereof. Figs. 5 to 8, inclusive, are detail sections, showing heads differing in construction for connection with the ends of the tubular body.

In carrying my invention into practice, I provide a platen comprising a tubular body 1, and end pieces or heads 2 and 3. The tubular body 1 is open at each end and is preferably formed by molding or otherwise of vulcanized rubber having embedded therein one or more concentric tubes or layers of wire cloth or other woven material 4 of any desired mesh. Preferably at least two layers or tubes of reticulated material are employed and spaced a sufficient distance apart to stay the body, while permitting the same to have sufficient resiliency to cushion the action of the type. This construction of tubular body or cylinder renders the same to a high degree non-resonant, so as to materially reduce or entirely deaden the sounds resulting in the ordinary construction from contact of the key bars therewith. This sound-deadening action is increased and promoted by supporting and backing the cylinder by a confined body of air, as herein-after described.

The end pieces or heads 2 and 3 are preferably formed of cast metal, and are connected

by a hollow or tubular core 5 adapted for the passage of the usual platen spindle. The core is preferably cast integral with the head 2 and is threaded at its free end, as shown at 6, to enter a threaded opening 7 in the head 3, whereby the latter is secured thereto. The heads are annularly grooved to receive and hold the ends of the cylinder or tubular body portion 1, and to this end each head is provided with a pair of inwardly extending flanges 8 and 9, forming an intervening groove 10 to receive the adjacent end of the cylinder.

In the form shown in Fig. 1, the ends of the cylinder are reduced to enter the grooves, and the inner surface of each flange 9 is beveled to crowd the same against the flange 8, thus securing a tight connection. After one end of the tubular body or cylinder has been slipped into the groove of the head 2, the head 3 is applied in position, and its groove receives the outer end of the cylinder, rubber or other suitable cement being employed to secure the said ends of the cylinder to the heads and to hermetically seal the joints between them. A similar cement is also provided between the threaded portions 6 and 7 to hermetically seal the joint between the head 3 and core 5 at their point of connection. By this construction a chamber 11 is formed within the platen between the cylinder or tubular body portion and core 5 to receive a confined body of air, which backs said cylinder and holds it inflated and at the same time permits it to yield sufficiently to cushion the action of the type bars, the escape of the confined body of air being prevented by hermetically sealing the joints in the manner described. The head 3 may be suitably constructed in practice for the application thereof to any particular type of end plate characteristic of different makes of typewriters.

Air is introduced into the chamber 11 through the medium of an air valve mounted upon the head 2, which valve comprises a casing 12 threaded into an opening 13 into said head and projecting interiorly and exteriorly through the same. The outer end of the casing is formed with a flange 14 acting as a stop to limit its inward insertion movement, and the inner portion of said casing is closed and provided with lateral or side ports 15 controlled by a disk valve 16. The valve is carried by a stem 17 arranged to slide

through the inner end wall of the casing and is normally held in closed position by a coiled spring 18, said spring encircling the stem between the valve and said inner end wall. 5 The outer end of the casing is designed in practice to be suitably constructed for the application thereto of the nipple of an air pump connection, whereby the chamber 11 may be charged with air in a convenient 10 manner, the valve opening to allow the air to enter, then closing to prevent its escape. The outer end of the casing forms a tubular receptacle 19 to contain a sealing medium of any kind to prevent the possible escape of 15 any air after the chamber 11 has been charged, and the joint between the casing and head 2 is sealed by the use of cement in the manner previously described.

It will thus be seen that a practically 20 noiseless or sound-deadening platen will be provided without the use of an interior air-holding and cushioning tube, and that the strength of the cylinder or tubular body portion and its capacity to sustain wear, as 25 well as its sound-deadening qualities, are increased by the use of the reticulated fabric embedded therein. If through wear it is found at any time necessary to replace the cylinder 1 with a new cylinder, the parts 30 may be disassembled by forcibly unscrewing the head 3, whereupon the cylinder may be disconnected and a new one applied to the heads in its place in the manner previously described.

35 In Figs. 5 to 8, inclusive, I have shown different ways of securing the ends of the cylinder to the heads, the construction shown in Fig. 5 differing from that shown in Fig. 1 only in omitting the beveled portion of the 40 flange 9, thus obviating the necessity of reducing the ends of the cylinder. In Figs. 6, 7 and 8 but a single flange is employed, the flange 9^a in Fig. 6 being internally beveled to form a seat face for the beveled end of the 45 cylinder, while in Fig. 7 the flange 9^b is set inwardly from the periphery of the head and engages the groove in the end of the cylinder, and in Fig. 8 the flange 9^c is set still farther inward and forms a support for the unreduced end of the cylinder which is secured upon the outer surface of the same. Any of 50 these or equivalent modes of connecting the ends of the cylinder with the heads may be employed.

Having thus described the invention, what 55 is claimed as new, is:—

1. A typewriter platen having an impact surface formed of hardened plastic material, said surface being provided with a plurality of layers of woven reticulated material embedded therein, said layers being in spaced relation with the strands of one arranged in planes crossing the interstices of the other to dispose their meshes out of alinement, whereby to provide a compound barrier against the 60 passage of sound waves.

2. A typewriter platen comprising heads, each provided with a pair of concentric inwardly extending flanges forming receiving grooves, the outer flange being internally 70 beveled or flared, a tubular non-resonant body provided with a layer of reticulated material embedded therein and having its end portion reduced and fitted within said grooves and clamped by the beveled faces of 75 the outer flanges against the inner flanges, a hollow stem integral with one of the heads and having a detachable connection with the other head, and means for inflating the platen.

3. A typewriter platen comprising end heads, one provided with a threaded opening, a tubular core or stem connecting said heads, a tubular, non-resonant body terminally secured to the heads and forming with said 80 heads an interior air chamber, and an inlet valve comprising a casing extending within and without the perforated head and externally threaded to engage the opening therein, said casing being provided with an 85 intermediate air port, an inner end wall, side ports in the inwardly extending portion, a stop flange on the outwardly extending portion to limit its inward movement, said outwardly extending portion being provided 90 with a chamber to receive a sealing medium, a valve mounted in the interiorly projecting portion and controlling the ports, a stem connected with the valve and slidably engaging the inner end wall, and a coiled spring 95 encircling the stem between the valve and inner end wall.

In testimony whereof, I affix my signature in presence of two witnesses.

WILLIAM R. VAN SLYKE.
